UNITED STATES PATENT OFFICE.

JOHN E. SPENCER AND GEORGE S. SPENCER, OF STRATFORD, CONN.

ADVERTISING-WINDMILL.

SPECIFICATION forming part of Letters Patent No. 276,640, dated May 1, 1883.

Application filed October 28, 1882. (No model.)

To all whom it may concern:

Be it known that we, JOHN E. SPENCER and GEORGE S. SPENCER, of Stratford, in the county of Fairfield and State of Connecticut, have invented a new and Improved Advertising-Windmill; and we do hereby declare the following to be a full, clear, and exact description of the same, reference being had to the accompanying drawings, making a part of this specification.

The object of our invention is to attract the particular attention of all persons upon a street or sidewalk in a town or city to the business carried on by the proprietor of a store, factory, or office. This we accomplish by constructing a machine which is operated by wind or other power, and having upon it a variety of objects likely to interest the passers by—namely, the four points of compass, as usually indicated by the letters N., E., W., S., an arrow or some other suitable index showing the direction from which the wind is blowing, the name of the firm or dealer, and the moving figure representing the article manufactured or sold, the whole being painted red, white, and blue, or some other gay and lively colors, and thus be quite sure to impress upon the mind of the observer the special class of goods advertised and the place where the same can be purchased, all of which will herein be fully explained and described.

In the accompanying drawings, Figure 1 is a side elevation of our improved advertising-windmill, showing all essential details of the same in their relative positions. Fig. 2 is a detached perspective view of the four arms to which are secured the letters indicating the points of compass, together with a portion of the central supporting-rod.

Similar letters of reference indicate corresponding parts.

A is a bracket, which is to be secured to the side wall of the building in which the goods advertised are manufactured or sold.

B is the base of the advertising-windmill, and is secured to the overhanging end of said bracket.

C is the body of the machine, having a shank, a, at the lower end, fitted to revolve freely in a hole in the base, the upper portion of the body

having a tapering end, to which is secured the pointer D.

E is the rod which supports the arms b b' b'' b''', to the ends of which are secured the letters N., E., W., S., indicating the four points of compass. Said rod passes freely through the center of the body C and shank a, but is fastened to the base B, into which the lower end extends. F is the hub of a revolving wind-wheel, having two or more fans extending from it, in the present case four fans, c c' c'' c''', all placed at an angle of about forty-five degrees with the vertical and horizontal plane. A shaft, d, extends from the center of the hub, which is fitted to turn freely in a hole in the body C. A gear-pinion, e, is secured to said shaft near the hub.

G is the vane of the machine, secured to the body opposite the wind-wheel.

H is a shaft fitted to turn freely in a bearing, f, on the top side of the vane G, and a bearing, g, attached to the body C.

h is a gear-pinion secured to the end of said shaft H, to be driven by gear e. To the opposite end of said shaft is secured the grooved pulley i.

I is the moving figure representing the goods manufactured or sold, which is secured to the top of the vane G by means of the rods j j', motion being imparted to the same by means of the belt k, which passes around pulleys i and l.

J is a plate hung upon the under side of the vane, and having upon it the name of the firm or dealer and the number of the factory or office.

This advertising-windmill may be exposed to the public by securing it in a vertical position on the top of a building, or on a bracket extending from the side walls of the same. In either case the letters indicating the four points of compass are to be placed and secured in their true positions, so as to give all observers a correct knowledge of the direction of the wind, which revolves the fan-wheel and operates the moving figure.

Having thus fully described our invention, we claim as new and desire to secure by Letters Patent—

An advertising-windmill for exhibiting goods, consisting of the combination of the fan-wheel F, the body C, adapted to revolve on the base

B, and having mounted on its top arms $b'b'b''b'''$ and pointer D, to indicate the four points of compass, and on its side the vane G, having the figure I secured to its upper side and the 5 name-plate J to its under side, gear-pinions e and h, and shaft H, adapted to operate figure I by means of pulleys i and l, substantially as

described and shown, and for the purpose set forth.

JOHN E. SPENCER.
GEORGE S. SPENCER.
